Max. Neumann

UNITED STATES PATENT OFFICE.

JOHN KOSTOLEK, OF NEW YORK, N. Y.

MILK-BOILER.

14,460.

Specification of Reissued Letters Patent. Reissued Apr. 23, 1918.

Original No. 1,255,921, dated January 29, 1918, Serial No. 146,633, filed February 5, 1917. Application for reissue filed February 11, 1918. Serial No. 216,634.

To all whom it may concern:

Be it known that I, JOHN KOSTOLEK, a citizen of the Empire of Austria, residing at New York, county of Bronx, and State 5 of New York, have invented certain new and useful Improvements in Milk-Boilers; and I do hereby declare the following to be a full, clear, and exact description of the invention, such as will enable others skilled in 10 the art to which it appertains to make and use the same.

This invention has reference to a novel milk boiler and pertains particularly to a device to be applied in a vessel containing 15 the milk to be boiled. The novel milk boiler prevents the boiling over of the milk from the vessel in which it is boiled.

When milk is boiled in an ordinary vessel and not carefully watched then, at a 20 certain moment, it bubbles up under the action of the heat applied thereto and boils over whereby part of the milk is lost. The overflowing part of the milk when reaching the hot stove or range is burned up and 25 causes bad odors. Furthermore the stove or range or the protective pan found in modern gas ranges has to be cleaned.

It is the special purpose of the present invention to produce a device to be applied in 30 milk boiling vessels for the purpose of avoiding the described boiling over of the milk, the loss of part of it and the inconveniences hereinbefore mentioned. The novel device when applied in a vessel containing milk to 35 be boiled prevents any loss even in the temporary absence of the cook or other person. The construction of the novel device is such that it preferably extends somewhat above the milk boiling vessel. It is broad 40 at the bottom and forms a narrow neck at the top and means are provided in its lower portion to insure a perfect circulation of the milk while heat is applied thereto and also means, which will hold the boiler steadily 45 on the bottom of the vessel while the boiling takes place and will prevent it from being thrown about and lifted during the boiling process. While a certain standard size of the device answers for certain 50 quantities of milk usually boiled by private people, larger quantities of milk require a larger size of the same. In addition to these main objects the construction of the device is so simple as to keep 55 the cost of production at a minimum and

care has been taken to produce a neat and desirable article, all as will be fully described hereinafter with reference to the accompanying drawing in which:

The figure in the drawing illustrates a 60 side elevation of a milk boiler according to my invention.

Similar characters of reference denote like parts.

The novel device to be applied in milk 65 boiling vessels usually is made of metal such as brass, copper, iron sheeting, aluminum and the like. It is preferably produced by stamping and may be finished as enameled iron ware or it may be electroplated, for 70 instance nickel-plated.

The device comprises a body portion *a* which is widest at the bottom and open there. From the bottom edge *b* the device is curved and further up gradually reduced in diameter forming at the top a narrow neck *c*. Thus the inner surface represents a 75 gradually curved surface along which the boiling milk quietly passes. In order to insure a free circulation of the boiling milk 80 the bottom portion of the device is provided with a plurality of notches *d* which are practically of semi-circular shape and widest at the bottom.

Assuming now that the device has been 85 placed in vessel containing milk and assuming that heat is applied to the vessel from below then the milk becomes hot and at a certain moment bubbles up and rises within the device and upon reaching the 90 open top end of the narrow neck *c* flows over and down on the outer surface of the device back into the vessel. In this manner no milk is lost even in the absence of the cook or other person.

Various sizes of the device are made. A standard size of about five and one-half inches in diameter at the bottom curved and reduced in an upward direction as shown, and having a neck of about one inch 100 in diameter at the top answers for a quantity of milk from one to three quarts. The height of this device is approximately six to six and one-half inches. If but little milk is in the vessel reaching not far beyond the openings *d* then the formation of steam may lift the device which is objectionable. If the openings *d* at the bottom are too large then the boiling will not go on as quietly as desired. The sizes men- 105

95

110

tioned above have been found by tests to produce good results.

The boiler is provided at the bottom with inwardly directed flanges *g* extending between the openings *d*. These flanges have even outer surfaces flush with the lower edge of the body portion *a* and are adapted to bear on the bottom of the vessel. Owing to the capillary action of the liquid between them and the said bottom, these flanges will adhere very firmly to the bottom while the boiling of the liquid proceeds whereby the device will be held from being thrown about or lifted so that a quiet boiling of the liquid can take place.

I claim as my invention:

1. In a liquid boiling utensil, the combination with a vessel having a flat bottom, of a flask open at top and bottom and having at its bottom a number of notches distributed around its circumference and flanges arranged between said notches, the outer surfaces of said flanges being in the same plane and flush with the lower edge of the flask and adapted to be held stationary on the flat bottom of the vessel by capillary action during the boiling of a liquid under treatment.

2. In a liquid boiling utensil the combination with a vessel having a flat bottom, of a curved flask open at top and bottom and consisting of a body portion widest at

the bottom and gradually reduced in diameter to form a comparatively very narrow

neck at its top, said flask having at its

bottom a number of notches distributed

around its circumference and inwardly di-

rected flat flanges arranged between said

notches, the outer surfaces of said flanges

being even and flush with the bottom edge

of the flask and adapted to rest on the flat

bottom of the vessel so that the capillary

action of the liquid between said flanges and

the bottom will hold the flask firmly in po-

sition during the boiling process.

In testimony whereof I affix my signature,
